2,556,096

POTTERY DRYING STOVE

Robert Alexander Maddock, Trentham, England

Application December 29, 1947, Serial No. 794,382
In Great Britain April 13, 1945

Section 1, Public Law 690, August 8, 1946
Patent expires April 13, 1965

4 Claims. (Cl. 34—105)

1

This invention relates to pottery drying stoves, and is chiefly although not necessarily exclusively concerned with the drying of articles of hollow ware such as cups.

The invention is concerned with the type of stove often known as a mangle, in which the articles to be dried are carried by moving shelves or racks through the drying chamber; usually the mangle type of stove is a somewhat tall and narrow chamber having a vertically moving conveyor carrying swinging trays or other suitable supports for the goods. The goods are loaded and unloaded through openings in the lower part of the stove and heat is introduced into the upper part of the stove. The conveyor carries the goods up from the loading opening into the upper drying zone of the stove and the dried goods are conveyed downwards past the unloading opening where they are removed. Sometimes a single opening serves for both loading and unloading.

The object of the invention is to facilitate the more effective drying of the ware in its travel through the stove.

A further object of the invention is to allow ware to be subjected to the direct action of the drying medium during a greater part of its travel through the stove, for example in its ascending or inward travel (away from the point of loading) and also in its descending or outward travel (back to the point of unloading).

A further object of the invention is to provide a stove in which the ware can be more quickly and easily loaded and unloaded by the workers.

A further object is to facilitate the removal of the pieces of ware from the moulds without having to remove the moulds from the stove, so that, for example, pieces such as cups can be sponged and fitted with handles while the now empty moulds continue their travel in the stove back to the point of loading, where they can be removed, re-filled and replaced to be dried again.

Other objects will become apparent from the ensuing description and claims.

This invention consists in a pottery drying stove in which the goods are carried through the stove by means of a swinging tray conveyor or other equivalent moving carrier wherein supports for the goods are provided of such a nature that the said goods are held in an inclined position, the heating or drying means being so arranged that the goods in their travel through the drying zone of the stove are subjected to the direct impingement of heat.

Referring to the drawings which form a part of this specification:

Figures 1, 2 and 3 are respectively a vertical sectional elevation, a side view, and a plan of 60

2

a vertical mangle stove in which the drying medium is hot air.

Figures 4, 5 and 6 are further vertical sectional elevations showing alternative arrangements.

Referring to Figures 1, 2 and 3 a mangle is provided with a loading opening 10 at one side and an unloading opening 11 at the opposite side, both near the bottom of the structure.

10 A vertical swinging tray type of conveyor 12 is arranged in the structure, ascending past the loading opening 10 and descending past the unloading opening 11. Each swinging tray is in the form of a V-section unit 13 adapted to receive moulds 14 and support them firmly in a position inclined at any suitable angle, say for example at about 45° to the vertical. In the stove above the openings air blowing units 15, 16 are provided having nozzles or louvres 17 or any other suitable provision whereby they direct hot air at substantially the same angle as that of the goods as indicated by the arrows, whereby the goods are subjected to direct impingements of the hot air from the unit 15 during the initial or ascending portion of their travel and from the unit 16 during the return or downward portion of their travel. The air blowing units 15, 16 are connected by ducts 18a, 18a, with a duct 18 through which 20 the hot air is blown by a circulating fan arranged at 19. The air is exhausted from the stove through the duct 20 leading to the other side of the fan 19 by way of a heater arranged at 21. The conveyor 12 is driven by a chain 25 drive 22 from a reduction gear and motor 23, the driving sprocket 24 being mounted on the same shaft 25 as the top sprockets 26 of the conveyor.

The air blowing units 15, 16 may be replaced 40 by radiant dryers or lamps 15b, 16b, Figure 4, for infra-red drying.

Where height is restricted the stove may have a horizontal drying zone as shown in Figure 5, the conveyor 12 being guided from the vertical 45 to the horizontal direction of travel and supported during the latter by guides 27. The moulds 14 are supported by inclined shelves 13a instead of by V-section units 13 of Figures 1-4. Figure 6 shows a similar stove incorporating lamps 15b, 16b as in Figure 4.

Having now described my invention, what I claim as new and desire to secure by Letters Patent is:

1. A pottery drying stove for articles of hollow ware comprising a casing having a loading opening and an unloading opening, a conveyor movably mounted within the casing, support devices swinging from said conveyor, each of said support devices being so formed that when a hollow ware article is placed therein it will

rest in an inclined position with respect to the conveyor with its open end facing upwardly and outwardly, heating means arranged within the casing in close proximity to said conveyor, the longitudinal axis of the heating means being substantially parallel to the axes of the hollow ware articles so that the hollow ware articles being dried are subjected to a direct impingement of heat from said heating means while travelling in their inclined position, the arrangement being such that the articles can be withdrawn from their moulds when they travel past the unloading opening, leaving the moulds still located in the supports.

2. A pottery drying stove for articles of hollow ware comprising a casing having a loading opening and an unloading opening, an endless conveyor movable in the casing, support devices swingably supported by said conveyor, each of said support devices being so formed that when an article of hollow ware is placed therein it will rest in an inclined position with its open end facing upwardly and outwardly, heating means disposed within the casing in close proximity to the conveyor, the longitudinal axis of the heating means being substantially parallel to the axes of the hollow ware to subject the hollow ware to a direct impingement of heat during movement of the conveyor, and additional heating means in said casing and so disposed with respect to the conveyor as to subject the hollow ware to direct impingement of heat after passing the first mentioned heating means.

3. A pottery drying stove for articles of hollow ware comprising a casing, a conveyor movable within said casing, support devices swingably mounted on said conveyor and adapted to receive the pottery mould and article, each of said support devices supporting the pottery article with the open end facing upwardly and outwardly in an inclined manner, and means for discharging heated air directly into the article, the longitudinal axis of the means for discharg-

ing the heated air being substantially parallel to the axes of the hollow ware articles.

4. A pottery goods drying stove comprising a chamber of tall narrow proportions, a travelling conveyor in said chamber, work supports on said conveyor, said work supports being adapted to hold the goods at an angle to the vertical run of the conveyor, said chamber having at least one opening to allow for the loading and unloading of goods, at least one casing in the chamber arranged above said opening, said casing being arranged and positioned so as to be in close proximity to goods carried past it by said conveyor, nozzles on said casing facing towards said conveyor, the longitudinal axis of the nozzles being substantially parallel to the axes of the goods, means for supplying hot air to said casing whereby said nozzles will direct the hot air inwardly towards the goods carried by the conveyor, said conveyor being adapted to carry the goods inclined outwardly towards said nozzles.

ROBERT ALEXANDER MADDOCK.
